UNITED STATES PATENT OFFICE.

ALBERT HENDERSON, OF PITTSBURGH, PENNSYLVANIA.

CONCRETE BUILDING BLOCK.

Application filed August 20, 1921. Serial No. 493,947.

To all whom it may concern:

Be it known that I, ALBERT HENDERSON, a citizen of the United States, residing at Pittsburgh, in the county of Allegheny and State of Pennsylvania, have invented certain new and useful Improvements in Concrete Building Blocks, of which the following is a specification.

This invention is a concrete building block which may be used in all building construction. The invention seeks to provide a block which may be formed of concrete or other cementitious material at a central plant and shipped therefrom to the point of use. The block is made in standard sizes so that engineering construction and architectural work will be greatly simplified and the user of the blocks will be enabled to eliminate the expensive waste of field forms and expedite erection. The invention insures a constant factor of safety and provides higher allowable concrete stresses. The invention is illustrated in the accompanying drawings, in which—

25 Figure 1 is a perspective view of one embodiment of the invention, and

Fig. 2 is a section on the line 2—2 of Fig. 1.

30 Fig. 3 is an end view showing a slightly different form of block.

The block, indicated as an entirety by the reference numeral 1, is formed in a suitable mold or otherwise at a central plant and is of a general rectangular form. The corners 35 of the block are all beveled, as shown at 2, and upon the four sides of the block are formed grooves 3 which impart to the block an appearance resembling that of brick or stone laid in courses. In the end of each 40 block is a depression or recess 5 defining a continuous marginal seating face and disposed in rectangular relation within each recess are lugs or projections 6 which have a height preferably equal to the depth of 45 the chamber or recess so that the outer surfaces of the lugs or projections will be flush substantially with the end surface or marginal seating face of the block. Openings or passages 7 are formed through the block 50 to permit the insertion of reinforcing tie rods therethrough when the blocks are assembled in a beam or column and these passages 7 may be of uniform diameter or flared toward their ends, as illustrated.

55 A reinforcing bail or ring 8 may be embedded in the block in the course of its manu-

facture and one or more of such reinforcing rings may be employed as desired and according to the size of the block. A keyway 9 may be formed around all the sides of the 60 block, if desired, so that, when the blocks are brought together in a wall or other structure, grout or green cement may be poured into the spaces defined by the keyways so as to firmly lock the blocks together. 65

In assembling the blocks in a wall or other structure, the end surfaces or the abutting surfaces of adjacent blocks are brushed lightly with grout so that they will readily unite when brought into juxtaposition. The 70 blocks will be made in various sizes so that any desired size of wall, column or beam can be produced by using the proper number of units of the proper dimensions.

The blocks may be laid like bricks and 75 no high degree of skill is required in their use. The keyway around the sides of the block will be advantageous when the blocks are united in a structure subjected to hydraulic pressure as a concrete key may be 80 thereby formed at all joints.

While I have referred to the block as a concrete block, it is to be understood that the invention is not limited to a block formed from cement but any plastic material may 85 be used as the substance from which to produce the block.

In Fig. 3, I have illustrated a hollow block having a single lug or projection and which may be employed where no great strength is 90 needed, and is especially adapted for use in conduits, pipes, telegraph poles, etc.

In all forms of the block, the grout area in the ends forms an invisible chamber between adjacent blocks assembled in a wall. 95

Having thus described the invention, what is claimed as new is:

1. A concrete building block provided in its end with a recess and spaced lugs within said recess, the outer surfaces of said lugs 100 being substantially flush with the end surface of the block and the lugs being spaced from the sides of the recess.

2. A concrete building block provided in its end with a recess and lugs within the recess, the side walls of the recess being parallel with the sides of the block and the outer sides of the lugs being parallel with the sides of the recess and the faces of the lugs being substantially flush with the end 110 surfaces of the block, and longitudinal passages through the block opening at their

ends within the recesses between the side walls of the same and the lugs.

3. A concrete building block of rectangular form having a continuous keyway formed in its ends and two of its sides, the ends of the blocks having recesses formed therein with the sides of the recesses parallel with the sides of the block.

4. A concrete building block provided in its end with a recess and lugs within the recess, the side walls of the recess being parallel with the sides of the block and the outer sides of the lugs being parallel with the sides of the recess and the faces of the lugs being flush with the end surfaces of the block; longitudinal passages through the block opening at their ends within the recesses between the side walls of the same and the lugs, and a keyway formed in the ends and two sides of the block and opening at its ends into the recesses in the ends of the block.

5. A concrete building block having a recess in each end thereof and defining a continuous marginal seating face, there being longitudinal passages extending entirely through the block and communicating with said recesses, and a projection on each end of the block within the recess with its outer surface disposed substantially flush with the adjacent seating face of the block.

6. A concrete building block having a recess in each end thereof and defining a continuous marginal seating face, there being longitudinal passages extending entirely through the block at the corners thereof and opposite each side wall and communicating with said recesses, and a projection extending from the wall of each recess and spaced from the adjacent marginal seating face of the block.

In testimony whereof I affix my signature.

ALBERT HENDERSON. [L.S.]
